UNITED STATES PATENT OFFICE.

EDWIN E. BARNEY, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 927,091.

Specification of Letters Patent.

Patented July 6, 1909.

Application filed April 5, 1907. Serial No. 366,506.

To all whom it may concern:

Be it known that I, EDWIN E. BARNEY, citizen of the United States, and resident of Syracuse, in the county of Onondaga and State of New York, have invented certain new and useful Improvements in Type-Writing Machines, of which the following is a specification.

My invention relates particularly to variable connections for typewriting machines and has for its main object to provide improved devices of the class specified.

To the above and other ends the invention consists in the features of construction, combinations of devices and arrangements of parts hereinafter fully described and particularly pointed out in the claims.

My invention is shown as applied to a Monarch typewriting machine and to the parts connecting the universal bar with the dog carrier or rocker, but the nature of the invention is such that it may be applied to other forms of writing machines and may be used to connect other members besides the universal bar and carriage feeding devices, whether said other means be in the Monarch machine or in other forms or kinds of writing machines.

In the accompanying drawings, Figure 1 is a front to rear central vertical sectional view of a Monarch typewriting machine showing my invention applied thereto, parts of the machine being omitted and parts broken away. Fig. 2 is a detached view drawn to an enlarged scale of the preferred form of my variable or extensible connection as seen from the right-hand side. Figs. 3, 4 and 5 are views of detached parts of the variable or extensible connection. Fig. 6 is a left-hand edge view of Fig. 2, parts being shown in section and a line locking hook which is a part of the line lock mechanism being indicated by dotted lines. Fig. 7 is a sectional view taken on the line x-x of Fig. 2 and looking in the direction of the arrow at said line.

Referring first to Fig. 1 of the drawings, the main frame of the machine is shown as comprising a base 1, corner posts 2 and a top plate 3. Key levers 4 coöperate with a fulcrum plate 5 mounted in the rear of the base, each of said key levers being provided with a restoring spring 6 and having pivoted to it at 7 a sub-lever 8. Each sub-lever is slotted at its lower end portion as at 9 to coöperate with a fixed abutment 10 and is connected at

its upper end by a link 11 to a type bar 12 pivoted in a hanger 13 which is secured by a screw 14 to a segmental type bar support 15 on which the type bar hangers 13 are arranged in segmental series. The type bars 60 are normally supported on a type rest 16 and are adapted, when suitably actuated, to coöperate with the front face of a rotary platen 17 mounted in a carrier or carriage comprising side bars 18 and a grooved rear 65 bar 19. Anti-friction balls 20 coöperate with the grooves in the bar 19 and with grooved track-ways 21 which are secured by screws 22 to standards 23 fixed to and rising from the top plate 3. A carriage feed rack 70 24 is supported on arms 25 pivoted at 26 to the side bars 18 of the carrier or carriage. Said rack 24 normally meshes with a feed pinion 27 which is operatively connected with a toothed escapement wheel 28 coöper- 75 ative with which are fed dogs 29 mounted at the top of a dog carrier or rocker comprising a vertically disposed arm 30, a rock shaft 31 and a horizontally disposed arm 32. The rock shaft of the dog carrier is pivoted at its 80 ends on ears 33 extending rearwardly from a supporting bracket 34 which is suitably secured to the frame of the machine. A restoring spring 35 normally maintains the dog 85 rocker in the position shown in Fig. 1. The forward end portion of the dog rocker arm 32 is provided with a curved tread 36. A universal bar 37 underlies all of the key levers and the spacing levers (not shown), said universal bar being supported on a universal 90 bar frame comprising a rock shaft 38 having its ends supported on fixed pivots and an arm 39 extending rearwardly from the middle of the rock shaft. A coiled restoring spring 40 tends to maintain the universal bar 95 37 normally in the position shown in Fig. 1.

The parts thus far described do not differ essentially from the corresponding parts of the Monarch machine and it is not deemed necessary to describe them in greater detail at this place.

I prefer to connect the carriage feeding device or dog rocker with the universal bar and the universal bar frame by a novel connection which is extensible so that its dimensions may be varied to vary the operation of the carriage feeding devices as compared with the operation of the type bars or printing mechanism. The novel connection is shown in detail in Figs. 2 to 6 inclusive and

comprises an upper member or bar 41 which has a broad upper end portion 42 terminating in a horizontally disposed ledge or lip 43 which is adapted to coöperate with the 5 curved tread 36 of the dog carrier. The member 41 is loosely connected with the arm 32 of said dog carrier by a pin and slot connection, being formed below the ledge 43 with a key-hole slot 44 which receives a 10 headed pin or screw 45 secured in the left-hand face of the arm 32 near its forward end. Near its lower end portion the member 41 is provided with a vertically disposed slot 46 and above the slot a pin or stud 47 projects 15 outwardly from the face of the member, said pin or stud being suitably secured to said member. A lower member or bar 48 is formed at its lower end with a round hole 49 which is adapted to receive a pin or stud 50 20 projecting laterally rightward from the arm 39 of the universal bar frame near the rear end of said bar (Fig. 1). A spring clip 51 suitably secured to the arm 39 serves to maintain the member 48 in engagement with 25 the pin 50. The construction is such that the member 48 is detachably and pivotally connected with the universal bar frame. The upper end portion 52 of the member 48 is widened into a plate-like part or plate as 30 shown most clearly in Fig. 4 and is provided with a vertical slot 53. Below said slot a pin or stud 54 projects from the face of the member in an opposite direction to the pin or stud 47 in the upper member. The pin 35 47 is adapted to engage with the slot 53 in the lower member and the pin 54 is adapted to engage with the slot 46 in the upper member as shown clearly in Figs. 2 and 6. Arranged between the upper and lower members or 40 bars 41 and 48 is an eccentric member or rotary device in the form of a sheet metal disk 55 which is clearly shown in Fig. 5. The disk is provided with a central perforation 56 and with two cam or eccentric slots 57 and 45 58. As will be understood from an inspection of Fig. 5 the distance of each of said slots from the center of rotation of said disk increases gradually from one end of said slot to the opposite end. An arm or finger piece 50 59 extends rearwardly from the periphery of the disk 55 and serves as a handle for manually adjusting the same. A bolt 60 serves as a support for the disk, said bolt, as is clearly shown in Fig. 6, passing through the 55 slot 46, thence through the central opening 56 in the disk and then through the slot 53, the axis of rotation of the rotary member or disk being transverse to the length of the two part link comprising the members 41 and 48. It is further to be noted that these members 60 are in the nature of plates and that the axis of the rotary device is at right angles to the faces of the plates or members 41 and 48. A nut 61 engages with threads on the end of 65 the bolt 60 and when tightened co-acts with

the head of the bolt to fasten or clamp the two members or bars 41 and 52 and the disk 55 tightly together and thus maintain them set in adjusted positions. The pin 47 in the upper member engages with the slot 57 in the 70 disk and the pin 54 in the lower member engages with the slot 58 in the disk. As shown in Fig. 6 the member 48 is bent or off-set as indicated at 48^a so that the body or lower portion of the bar is in the same plane as in 75 the upper member or bar 41.

Below the slot 44 the member 41 is provided with a vertical slot 62 which receives a headed screw 63, the latter serving as a support for a line locking member or lug of improved construction, preferably formed of sheet metal and comprising an engaging finger 64, a laterally bent portion 65, a portion 66 parallel with the engaging finger and a short laterally bent portion 67 parallel 80 with the portion 65. The portion 66 with the portions 65 and 67 at its ends forms a U-shaped engaging part which fits over and closely embraces the member or bar 41, the latter at this point being rectangular in cross 85 section. The line locking member is adapted to be clamped to the bar 41 by a nut 68 which coöperates with the bolt 63. It will be understood that by loosening the nut 68 the line locking member may be shifted up 90 and down lengthwise of the member 41, the up and down or right line motion being limited by the length of the slot 62. It will also be understood that rotary motion of the line locking member, that is motion about 95 the bolt 63 as a pivot, will be prevented by the portions 65 and 67 which contact with the edges of the member 41. The finger portion 64 of the line locking member is adapted to coöperate with a hook-like device 100 69 which is part of a line locking mechanism like that disclosed in the patent to Felbel, No. 667,928, dated September 18th, 1900.

It will be understood that when any key lever is operated it causes a depression of the 110 universal bar frame and a lowering of the extensible or variable connection comprising the bars 41 and 48, the disk 55 and the bolt and nut which normally clamp the members and the disk together making them act in 115 effect as a single piece. The lowering of the connection causes the lip or ledge 43 to contact with the tread 36 of the dog carrier, rocking the latter and causing the feed dogs 29 to co-act with the escapement wheel 28 120 in the usual manner. When the depressed key lever is released the dog carrier is restored to normal position by its restoring spring 35, and the universal bar frame and the novel connection are restored to normal 125 positions by the combined action of the restoring springs 35 and 40. It will further be understood that variation in the operation of the dog carrier or rocker will take place according as the lip 43 at the top of the 130

novel connection stands at a greater or less distance normally from the tread 36 of the dog carrier, as thereby the dog carrier is caused to participate to a less or greater extent in the movement of the universal bar frame and the printing mechanism and the feed dogs 29 are moved forward transversely of the escapement wheel 28 a less or greater distance. Preliminary to adjusting the relation between the dog carrier and universal bar either initially or to compensate for wear or to suit the particular requirements of the operator it is only necessary to loosen the clamping nut 61 sufficiently to permit a manual rotary movement to be communicated to the eccentric device or disk 55. By moving the handle 59 of the disk upwardly it will be apparent that the eccentric slots 57 and 58 will coöperate with the pins 47 and 20 54 respectively to force said pins apart, and as said pins are fixed to the upper and lower members of the connection it will be clear that said connection will be lengthened or extended. The lower member 48 is held from movement by the pin 50 on the universal bar frame and consequently any increase in the length of the connection as a whole will result in the upward movement of the ledge 43, causing it to separate to a greater extent from the tread 36 on the dog carrier. Similarly a downward movement of the handle 59 will result in drawing the pins 47 and 54 closer together and in a consequent lowering of the lip or ledge 43. It will further be apparent that even when the clamping nut 61 is loosened the disk 55 will coöperate with the pins 47 and 54 to maintain the upper and lower members in any relation to which they may be brought by the rotary movement of the disk, so that the adjustment of the connection may be tested before the parts are set or clamped by the tightening of the nut 61.

The construction above described forms a comparatively simple and at the same time a very convenient method of regulating the operation of the escapement devices. As has been heretofore stated the invention is not confined however to connecting the devices shown but may be employed in other parts of typewriting machines wherever found convenient and useful.

Various changes may be made without departing from the spirit and scope of my invention.

What I claim as new and desire to secure by Letters Patent, is:—

1. In a typewriting machine, the combination of a carriage, carriage feeding devices, a key actuated universal bar, and a connection between said universal bar and certain of said carriage feeding devices, said connection comprising two slotted members each having a pin or stud coöoperative with the slot in the other member, and a rotary

adjusting device having eccentric slots coöoperative with the pins of said members to vary the relationship between said members.

2. In a typewriting machine, the combination of a carriage, carriage feeding devices, a key actuated universal bar, a connection between said universal bar and certain of said carriage feeding devices, said connection comprising two slotted members each having a pin or stud coöoperative with the slot in the other member, a rotary adjusting device having eccentric slots coöoperative with the pins of said members to vary the relationship between said members, and a clamping bolt or nut for maintaining the members and the device set in adjusted positions.

3. In a typewriting machine, the combination of a carriage, carriage feeding devices including a pivoted dog rocker, a key actuated universal bar, a slotted bar pivotally connected with said universal bar and provided with a pin or stud, a slotted bar provided with a pin or stud and having a variable relationship with said dog rocker, and a hand actuated rotary disk arranged between said bars and provided with eccentric slots coöoperating with the pins or studs on said bars, the pin or stud of each bar also coöperating with the slot in the other bar.

4. In a typewriting machine, the combination of a carriage, carriage feeding devices including a pivoted dog rocker, a key actuated universal bar, a slotted bar pivotally connected with said universal bar and provided with a pin or stud, a slotted bar provided with a pin or stud and having a variable relationship with said dog rocker, a hand actuated rotary disk arranged between said bars and provided with eccentric slots coöoperating with the pins or studs on said bars, the pin or stud of each bar also coöperating with the slot in the other bar, a bolt on which said disk is rotatable, and a nut coöoperative with said bolt to clamp or set said bars and said disk in adjusted positions.

5. In a typewriting machine, the combination with a universal bar, carriage feeding devices and a bar rectangular in cross section and comprised in the connection between the universal bar and certain of the carriage feeding devices, of a member having a pin and slot connection with said bar and partially embracing said bar so as to be capable only of right line motion on said bar, said member being coöoperative with the line locking mechanism of the machine.

Signed at Syracuse, in the county of Onondaga and State of New York this 2nd day of April A. D. 1907.

EDWIN E. BARNEY.
